(57) CLAIM

The ornamental design for a ribbon chain, as shown and described.

DESCRIPTION

FIG. 1 is a front view of a ribbon chain showing our new design;

FIG. 2 is a back view thereof;

FIG. 3 is a right view thereof;

FIG. 4 is a left view thereof;

FIG. 5 is a top view thereof;

FIG. 6 is a bottom view thereof; and,

FIG. 7 is a front view thereof.

Those portions of the figures that are presented in broken lines merely illustrate the environment of the design and are not part of the claimed design.
